[57] **CLAIM**

The ornamental design for a multi-function game call, as shown and described.

DESCRIPTION

FIG. 1 is a top perspective view of my multi-function game call; showing the new design, with the band broken away in the center to indicate indeterminate length;

FIG. 2 is a top perspective view thereof;

FIG. 3 is a bottom perspective view thereof;

FIG. 4 is a perspective view thereof;

FIG. 5 is a top plan view thereof;

FIG. 6 is a side elevational taken generally from the left side of FIG. 5 and looking towards the right;

FIG. 7 is a side elevational taken generally from the right side of FIG. 5 and looking towards the left;

FIG. 8 is a bottom plan view thereof;

FIG. 9 is an end elevational taken generally from the top of FIG. 5 and looking down; and,

FIG. 10 is an end elevational taken generally from the bottom of FIG. 5 and looking up.
